(57) **CLAIM**

The ornamental design for a frame for an area light, as shown and described.

DESCRIPTION

FIG. 1 is an overall perspective view of a frame for an area light showing my design with a portion of the area light shown in broken lines;

FIG. 2 is a front elevational view of the frame of FIG. 1; FIG. 3 is a rear elevational view of the frame of FIG. 1; FIG. 4 is a top plan view of the frame of FIG. 1;

FIG. 5 is a bottom plan view of the frame of FIG. 1; and FIG. 6 is a left side elevational view of the frame of FIG. 1, the right side being a mirror image;

FIG. 7 is an overall perspective view of an alternative embodiment of a frame for an area light showing my design with a portion of the area light shown in broken lines;

FIG. 8 is a front elevational view of the frame embodiment of FIG. 7;

FIG. 9 is a rear elevational view of the frame embodiment of FIG. 7;

FIG. 10 is a top plan view of the frame embodiment of FIG. 7; and,

FIG. 11 is a bottom plan view of the frame embodiment of FIG. 7.

The left side elevational view of the frame embodiment of FIG. 7 is shown in FIG. 6, the right side being a mirror image.

The broken lines in the Figures are shown for illustrative purposes only and do not form part of the claimed design.
